SPINAL MASSAGE APPARATUS

Thomas M. Parker, Evanston, Ill.

Application February 11, 1932, Serial No. 592,227

11 Claims. (Cl. 128—70)

My invention relates to therapeutic appliances, and more particularly to apparatus for spinal correction, and my main object is to provide an apparatus of this kind which provides a set of applicators which are adjustable for proper locations relative to the spinal processes.

A further object of the invention is to provide means for vibrating the applicators whereby to impart a massaging action to the muscles of the spinal processes.

A still further object of the invention is to incorporate heat units in the applicators for the purpose of increasing the circulation in the muscles of the spinal processes as they are massaged.

A final and important object of the invention is to design the apparatus on simple and rugged lines and without parts of an intricate or complicated nature.

With the above objects in view and any others that may suggest themselves from the specification and claims to follow, a better understanding of the invention may be had by reference to the accompanying drawings, in which—

Fig. 1 is a plan view of the novel apparatus partly broken away;

Fig. 2 is a vertical section of the same, including a sheet or cloth upon which the subject lies when taking the massage treatment;

Fig. 3 is an enlarged elevation of one of the applicators;

Fig. 4 is an edge view thereof; and

Figs. 5 and 6 are, respectively, sections on the lines 5—5 and 6—6 of Fig. 4.

Spinal massage has been found beneficial for the relief of various conditions, such as bad posture, tension of the nervous system as found in insomnia, fibrosis of the spine, and other tendencies toward body disorders or premature senility.

While various methods and expedients have been applied to secure beneficial results, I have found none which combines all the factors productive of best results and have accordingly designed the novel apparatus to include such factors and fully accomplish the objects outlined.

Referring specifically to the drawings, the novel apparatus fundamentally involves a base 10 from which end posts 11 and 12 rise to support a table 13. The post 12 corresponds to the frontal or head-end of the table, and has an extension 12a serving with the top of the post as a rest for a pillow 14, on which the subject rests his head while lying on his back upon the table. That part of the table 13 which is under the trunk of the subject is open, as indicated at 13a.

The apparatus is built with a drop frame 15 extending from the head post 12 to about middle distance, where a support 16 occurs between the table and the drop frame. The drop frame is preferably made with side walls 15a to enclose a series of applicators 17, which will now be described.

Each applicator is comprised of a pair of inverted substantially U-shaped metallic hoods having elongated substantially cylindrical tops as clearly shown in Fig. 4 and mounted over shanks 18 whose upper ends are preferably rounded as indicated at 18a in Fig. 3. The hoods 17 are rockably mounted on the shanks by means of fulcrum screws 19, so that they may be tilted or swung laterally to a limited extent. Each of the applicator hoods or components contains an electrical heat unit, which is supplied by conductors 20 which lead from a main current source 21, the latter including an ammeter or other instrument 22 to indicate the amount of current entering the applicators, that the degree of heat therein may be determined.

The applicator series is intended to receive a vibrating motion in a longitudinal direction, and this I impart jointly to the applicators by means of a bar 23 extended longitudinally between the pairs of applicators. The bar contains end couplings 23a for rod extensions 24 at the front and rear, these being slidable in bearings 25 built into the post 12 and support 16. The rear rod 24 pivotally connects at 26 with a pitman 27 leading to a pulley 28 carried by a hanger 29 from the table 13. The pulley is built up on its face with retainers 28a for a bolt which passes through the corresponding end of the pitman to receive a nut 28b. By sliding the bolt in the retainer, the lateral adjustment of the pitman relative to the pulley 28 is changed to suit the length of the vibrations desired to be imparted to the pitman. The pulley 28 is connected by a belt 30 to the pulley 31 of a speed reducing unit 32, the latter being driven by a motor 33. The vibrating action of the bar 23 is transmitted to the shanks 18 of each pair of applicators 17 by means of screws 34 and 35 extending from opposite sides of the bar and passing through vertical slots 18b in the applicator shanks. To permit the vibration of the applicators, each pair is pivotally mounted by means of a bottom bolt 36 to a block 37 which is stationary in a lateral sense. However, the block may be vertically adjusted to raise or lower the pair of applicators, such adjustment being procured by a jack. As indicated in Figs. 1 and 2 the jacks for the applicators are preferably of doubled ex-

100
105
110

tension type numbered 38 with suitable bases 38a and handwheels 38b. It will be evident that the slotted formation 18b of the shanks 18 will permit the applicators to be raised or lowered without affecting their connection with the vibrating bar 23. It should be understood that I make no claim for the particular type of jack employed, simply illustrating the preferred one as a matter of example.

10 It is also desirable that each pair of applicators should be made with its components adjustable toward and away from each other. For this purpose, I provide blocks 39 to act as fillers for the shanks 18 in the zone of the screws 34 and 35, 15 the shanks being preferably made of hollow sheet metal construction as indicated in Fig. 5. The screws 34 and 35 are threaded through the respective blocks 39 and their threads run in opposite directions. They are anchored by cross pins 20 35a in the ends of a bushing 35b which passes loosely through the bar 23. One of the screws is extended through a vertical opening in one of the walls 15a of the drop frame 15 to receive a hand-knob 40. It is seen that by turning the latter, both screws will be rotated through their common connection with the bushing 35b; however, the screws being of reverse threads, the applicator components will either gather or spread according to the direction of rotation. The 25 blocks 39 are sufficiently loose in the shanks 18 to permit the shanks to assume a limited amount of angularity due to the gathering or spreading of the applicator components, since these are pivotally united to their lower sections as indicated at 18c in Fig. 4.

30 The pivotal mounting at 19 of the applicator hoods 17 is also adjustable by a control now to be described. This control originates with a thumb screw 41 which is threaded through a cross head 42 secured between the lower sections of the shanks 18, these containing filler blocks 43 in order that screws 44 may pass through the latter and into the sides of the cross head to secure the same, as clearly shown in Fig. 6. The remote end of the thumb screw 41 makes a ball-joint 41a with the lower end 45a of a vertical frame 45 which extends along the rear of each applicator bar and rises into the hoods 17 in the form of an arch 45b formed with bosses 45c suitable for receiving screws 46 from the side of the applicator to firmly secure the same to the arch 45b. The frame 45 is thus made a depending and rigid extension of the hood, and it will be seen that its lower end may be used as a lever through the operation of the thumb screw 41 to swing the frame 45 toward or away from the applicator with the result that the hood thereof is rocked to different angular positions. It will be understood that the swinging action of the frame 45 is so limited as to be free of binding action at the ball-joint.

35 The spacing of the applicator hoods 17 is so calculated as to locate them opposite the spinal processes of the subject, yet amply clearing the line of vertebrae which runs between such processes. The rounded form of the hoods is designed to best fit the spinal processes, but a suitable sheet or cloth 47 is preferably laid over the array of applicators, as shown in Fig. 2, in order that the subject's back may be cushioned somewhat as it makes contact with the applicators. Also, such sheet or cloth will temper the heat of the hoods in case the subject is sensitive to it. As indicated in Fig. 1, some of the applicators are spread more than the others, this being made

possible by the adjustment described above, and serving to suit different locations of treatment for one subject or another. Also, the angular individual adjustment of the applicator hood adapts them for the greatest comfort and most favorable working angle of the applicator.

80 It will be seen that by means of the novel apparatus, I am able to procure a vibratory massage which is parallel to the fibres of the longitudinal muscles that support the spine, yet to massage as close to the spinal processes as possible without irritating them, passing directly posterior to the spinal nerves, ganglia, and sympathetic nerve chain. Further, imparting heat to the applicators induces a greater supply of blood and circulation thereof in the zone massaged, relieving hypertension, a condition where the nerve centers lack blood, and fibrosis of the spine. Further, with the spreading adjustment of the applicator components, not only can an irregular course of massage be secured to suit the particular subject, but some of the applicators can be spread out or removed at zones where treatment is not wanted or considered desirable, so that only the balance of the applicators act. Finally, 90 the novel apparatus is a structure of simplicity and durability, having no delicate complicated or highly accurate parts, which require special attention or are subject to disorder.

95 I claim:—

100 1. A spinal massage applicator comprising a pair of companion shanks, applicator units carried in the top of said shanks, a vibratory bar between the shanks, the latter being vertically slotted, and stems extending from the vibratory bar through the slots in the shanks, whereby to connect the shanks horizontally with the bar for vibration and give the shanks vertical clearance relative to the stems by means of said slots.

110 2. A spinal massage apparatus comprising a pair of companion shanks, applicator units carried in the top of the said shanks, a vibratory bar between the shanks, the latter being horizontally tapped in registration, a bushing freely disposed in the bar, and reversely threaded screws 115 extending from the bushing and threading into the respective shanks, whereby to gather or separate them according to the direction in which the screws are turned.

120 3. The structure of claim 2, and means to rigidly connect the screws with the bushing.

125 4. The structure of claim 2, the shanks being of hollow metallic construction, and blocks inserted in the shanks in the zone of passage of the screws, said blocks containing the tapped portions for the screws.

130 5. The structure of claim 2, the shanks being of hollow construction and vertically positioned, and pivot means between the shanks for the lower sections, and blocks inserted in the shanks in the zone of passage of said screws and tapped to receive the same, said blocks being sufficiently loose in the shanks to permit the pivotal gathering or separation of the shanks as induced by the rotation of the screws without binding the latter.

135 6. A spinal massage apparatus comprising a pair of companion shanks, rockable hoods carried at the top thereof and serving as applicator units, downward extensions of the hoods alongside the applicator shanks, a cross head carried by the lower sections of the shanks, a thumb screw threaded horizontally through the cross head, and a ball-joint between the thumb screw and the lower portions of the extension, the opera-

- tion of the thumb screw swinging the extension with the effect of rocking the hood.

7. In massage apparatus of the class described, the combination with a frame including a supporting table having an opening therein for access to the body portion to be treated, of a plurality of applicators arranged in said frame at said opening, each of said applicators comprising a pair of vertical shanks, a support at the lower ends of said shanks to which the shanks are pivoted to permit swinging movement of said applicators longitudinally of said opening, said shanks also being mounted for relative lateral movement with respect to each other to vary the spacing therebetween, means for effecting said lateral movement between said shanks, a hood carried at the top of each of said shanks and serving as an applicator unit, said hoods being tiltably mounted on said shanks, whereby to vary the angle of inclination of the hoods and thereby vary their angle of presentation to the body under treatment, and means for tilting said hoods on said shanks.

8. In massage apparatus of the class described, the combination with a frame including a supporting table having an opening therein for access to the body portion to be treated, of a plurality of applicators arranged in said frame at said opening, each of said applicators comprising a pair of vertical shanks, a supporting block arranged between the lower ends of said shanks and to which the shanks are pivoted to permit swinging movement of said applicators longitudinally of said opening, said shanks also being pivoted with respect to said supporting block for relative lateral movement with respect to each other to vary the spacing therebetween, means for effecting said lateral movement between said shanks, a hood carried at the top of each of said shanks and serving as an applicator unit, said hoods being tiltably mounted on said shanks, whereby to vary the angle of inclination of the hoods and thereby to vary their angle of presentation to the body under treatment, and means for tilting said hoods on said shanks.

9. In massage apparatus of the class described, the combination with a frame including a supporting table having an opening therein for access to the body portion to be treated, of a plurality of applicators arranged in said frame at said opening, each of said applicators comprising a pair of vertical shanks, a support at the lower ends of said shanks to which the shanks are pivoted to permit swinging movement of said applicators longitudinally of said opening, a hood carried at the top of each of said shanks and

serving as an applicator unit, said hoods being of inverted substantial U-shape and provided with elongated substantially cylindrical tops to serve as applicator units, said hoods being tiltably mounted on said shanks, whereby to vary the angle of inclination of the hoods and thereby to vary their angle of presentation to the body under treatment, and means for tilting said hoods on said shanks.

10. In massage apparatus of the class described, the combination with a frame including a supporting table having an opening therein for access to the body portion to be treated, of a plurality of applicators arranged in said frame at said opening, each of said applicators comprising a pair of vertical shanks, a support at the lower ends of said shanks to which the shanks are pivoted to permit swinging movement of said applicators longitudinally of said opening, a hood carried at the top of each of said shanks and serving as an applicator unit, said hoods being of inverted substantial U-shape and provided with elongated substantially cylindrical tops to serve as applicator units, said hoods being tiltably mounted on said shanks, whereby to vary the angle of inclination of the hoods and thereby to vary their angle of presentation to the body under treatment, and a common actuating device operatively related to said hoods for tilting the same on said shanks.

11. In massage apparatus of the class described, the combination with a frame including a supporting table having an opening therein for access to the body portion to be treated, of a plurality of applicators arranged in said frame at said opening, each of said applicators comprising a pair of vertical shanks, a support at the lower ends of said shanks to which the shanks are pivoted to permit swinging movement of said applicators longitudinally of said opening, said shanks also being mounted for relative lateral movement with respect to each other to vary the spacing therebetween, means for effecting said lateral movement between said shanks, an inverted U-shaped hood carried at the top of each of said shanks and being tiltably mounted thereon, said hoods also having elongated substantially cylindrical tops and serving as applicator units, an operating connection in engagement with each of said hoods to tilt the latter with respect to the vertical shank which supports the same, and a common operating device associated with said operating connections to actuate the latter and thereby rock the hoods in relation to the shanks.

THOMAS M. PARKER.
